GOLF BALL WARMER

Jackson P. Seals, Richmond, Va.

Application December 28, 1938, Serial No. 248,140

6 Claims. (Cl. 263—5)

This invention relates to golf ball warmers and has for its object the provision of a warmer of small size that may be carried in the pocket of the player. A primary object of the invention 5 is to provide an economical warmer using a spirit fuel such as gasoline, alcohol or the like.

Another object is to provide a warmer having a hinged lid whereby a golf ball may be easily inserted or removed.

10 It is well known by golf players who play in the winter time that the ball cannot be driven as far as in the summer when the ball is warm. The reason for this is that a cold ball does not have the elasticity of a warm ball and it has 15 been the practice by players who realize this to warm up the golf balls before leaving the club house and to wrap the balls in towels so that the heat is retained until ready for use. By my invention I make it unnecessary to go to this trouble and in addition my device may be used 20 by the player at the same time to keep his hands warm.

Figure 1 is a front view of my warmer.

Figure 1 is a side view, partly in section, of the device.

25 Figure 3 is a top plan view of the device.

Figure 4 is a view of the device inclosed in a heat insulating bag.

The warmer consists of a body 10, having a 30 wick 11 reaching down into and preferably filling the fuel containing interior of the body. The wick cover 12 is preferably removable so as to facilitate filling the body with liquid fuel.

The top 14 of the warmer consists of a collar 35 portion 15 adapted to fit snugly over the top portion 16 of the body and has an enlarged spherical section 18 for receiving a golf ball. The collar portion is extended to provide communication between the flame and the spherical interior of the ball container. One-half 19 of the section 18 is hinged at 20 so as to swing open and permit the insertion of a golf ball into the cavity 18. A latch 22 is provided for securing the lid portion 19 in closed position.

45 The interior of the cavity 18 is preferably lined with heat insulating material such as asbestos cloth as shown at 25. This cloth preferably extends across the open throat as at 26 to insulate the ball from the direct heat of the flame indicated at 27. It is also necessary to provide vents in the portion 14 as shown at 30 and 31.

The operation of the device depends upon the 50 generation of gas by the heat of the flame and for this reason it is found best to place the device in an open top fabric bag 34 as shown in Figure 4. If a cold hand is placed against the body 10 the flame may be seen to diminish, almost immediately, to about half-size, due to the

transmitting of heat from the body of the device to the cold hand; this heat otherwise acts as a gas generator. If a layer of cloth is placed between the body 10 and the cold hand then the rate of transmission of heat is greatly reduced so that the rate of generation of gas is maintained and the flame continues to burn almost at its normal size. When the device is in operation and placed in a bag it may be carried in the pocket and will continue to operate satisfactorily as long as the bag is open as at 36 but if the top of the bag is closed the flame may be extinguished. In the absence of a bag it is found that a fabric cover 38 will give satisfactory results even though it covers only the body 15 portion 10 as shown in Figure 2.

What I claim is:

1. In a device of the character described, a casing formed of a plurality of relatively movable parts, said casing having therein an upper chamber to receive a golf ball to be warmed, a lower chamber to serve as a fuel receptacle, and a space within the upper chamber formed by cooperating depressions in two of said relatively movable parts so as to hold a golf ball between them, and a heat producing element within the casing 20 receiving fuel from said receptacle for warming the upper chamber.

2. The device of claim 1 in which the casing is relatively shallow in depth except for the 30 bulge to receive the golf ball and each of the two depressions is spherical in shape and roughly as deep as the depth of the casing so that the depth of the casing at the ball carrying space is at least twice the thickness of the rest of the casing.

3. A holder for association with a conventional heater to warm a golf ball in cold weather to increase its elasticity, comprising a body having an open end to engage the heater, and a cover for said body, said cover and body having cooperating spherical depressions therein to receive between them a golf ball to hold it in position to receive heat generated by said heater.

4. The device of claim 3 in which the body 45 is metal and telescopes over the heater.

5. The device of claim 3 in which the body is metal, telescopes with the heater for snug engagement and has a plurality of slotted vents adjacent the heat generating portion of the 50 heater.

6. The device of claim 3 in which the body is of metal snugly fitting the heater by having a telescoping engagement therewith, and a heat insulating lining between the ball and the heat generating portion of the heater.
